UNITED STATES PATENT OFFICE.

AUGUST SUNDH, OF YONKERS, NEW YORK, ASSIGNOR TO OTIS ELEVATOR COMPANY, OF JERSEY CITY, NEW JERSEY, A CORPORATION OF NEW JERSEY.

ALTERNATING-CURRENT MOTOR-CONTROLLER.

No. 869,943.

Specification of Letters Patent.

Patented Nov. 5, 1907.

Application filed December 18, 1905. Serial No. 292,123.

To all whom it may concern:

Be it known that I, AUGUST SUNDH, a citizen of the United States, residing in the city of Yonkers, in the county of Westchester and State of New York, have invented a new and useful Improvement in Alternating-Current Motor-Controllers, of which the following is a specification.

My invention relates to motor-controlling apparatus and is herein shown as applied to a motor for driving elevator hoisting apparatus, but its application may be general.

One of the objects of my invention is the provision of means for controlling the starting and acceleration of electric motors, said means to be dependent upon suction apparatus.

A further object of my invention is the provision of a master electro-responsive device for operating the suction device which in turn shall control auxiliary suction devices to effect a step-by-step cutting out of the opposition element in circuit with the motor.

Other objects of the invention will appear hereinafter, the novel combinations of elements being pointed out in claims.

In the drawing, I have shown a transformer T connecting the mains from a source of alternating current supply to the mains a, b, c through the three-pole switch L.

C designates an elevator car which is connected to the hoisting apparatus H to which is connected in turn the driving motor M herein shown as an induction motor of the three-phase type. The hoisting apparatus H may be of any suitable construction, and I have shown a three-phase motor M merely to illustrate the application of my invention, as said motor may be single-phase, two-phase or any other phase, or if desired it may be a direct current motor.

In the car C is a reversing switch comprising a pivoted lever 6 carrying wipers 5 and 5' and the fixed contacts 4, 4', 8, 8' and contact strips 2 and 3. When the lever 6 is moved to the right, wiper 5' will connect the strip 3 with the contact 4' and the wiper 5 will connect the contact-strip 2 with the contact 8'. One of the mains, as a, is permanently connected to one of the motor terminals, as that designated 1. With the switch-

lever 6 in its right-hand position, the circuit will be completed from main b, through strip 2, wiper 5, contact 8', and wires 11' and 11 to motor-terminal 12. Another phase circuit will be closed from main c through contact-strip 3, wiper 5', contact 4', and wires 7 and 9 to motor-terminal 10. When the lever 6 is moved to the left, it is obvious that the connection of the mains b and c to the motor-terminals 12 and 10 will be reversed. This will effect a reversal of the rotating field and consequently also of the rotor of the motor.

If desired, any well-known system of reversing switches may be connected between the switch in the car and the driving motor. For the sake of simplicity, I have shown a manual switch in the car which will directly reverse the motor. By a slight change in the connections, such a manual reversing switch could be adapted to direct current or other kinds of motors.

In this instance, I have shown an opposition element R in the form of a resistance, although the same may be inductance or other means for limiting the current which will be induced by the stator in the rotor. If desired, this opposition element could be placed in the primary circuits, or if a direct current motor is used it would preferably be placed in series with the motor armature. Furthermore, said opposition element could be replaced by a transformer having its primary or secondary divided into a plurality of sections adapted to be cut out or inserted in order to regulate the voltage applied to the motor.

As shown in the drawing, the terminals 19', 20' and 21' are connected by the leads 19, 20 and 21, respectively, to the rotor of the motor M. The resistance R may be star-connected as shown, or delta-connected, or of any other desired form. It is here shown star-connected and divided into a plurality of sections which are connected to fixed contacts. The central section of the resistance is connected by the wires 22, 23 and 24 to the fixed contacts 22', 23' and 24', respectively, while the intermediate sections are connected by the wires 29, 30 and 31 to the fixed contacts 29', 30' and 31', respectively. The terminals of the opposition element R are in effect connected by the wires 33, 34 and 35 to the fixed contacts 33', 34' and 35'. It will now be seen that when the groups of fixed contacts are successively electrically connected, the resistance R will be short-circuited or cut out step by step from in circuit with the rotor of the motor M.

Connected across two of the mains or phases by means of the leads 13 and 14, as for example between the wires 11 and 9, I have shown a plurality of electromagnets. The solenoids of all of these electromagnets are connected in parallel, the solenoid 15 of the last electromagnet having preferably the greatest number of ampere turns.

Inasmuch as I have shown an alternating current electric motor, I have illustrated electromagnets which are particularly adapted for alternating currents, in this case such currents being single-phase. The frames 40 and 40' are preferably laminated and so also the cores 39 and 60, but if direct currents are used for operating these electromagnets, solid frames or cores may be used if desired.

The electromagnetic switches 26, 27 and 28 may be increased or decreased in number, and since their con-

struction is similar, only one will be described. Each comprises a laminated frame 40 in which is placed a solenoid as 18 and a core 39 which is preferably laminated. To the upper end of the core 39 is secured a piece of 5 non-magnetic material 38 to support the cap 63, the spring 37 and the bridge-piece or contact-maker 36. When the solenoid 18 receives current and the core 39 allowed to be moved to its uppermost position as hereinafter explained, the bridge-piece 36 will electrically 10 connect the fixed contacts situated directly above the same. The spring 37 has the effect of taking up the vibrations of the core 39 due to the alternations of current in coil 18, and thus maintain said bridge-piece 36 in firm engagement with the fixed contacts which it 15 connects. To the lower end of the core 39 is connected as by means of a pivot 41, a piston 42 which is adapted to move in the cylinder or cup 46. A passage 43 extends from the upper side of the piston 42 to its lower side or to the chamber 45. The upper end of this passage 20 is normally closed by a spring-pressed ball-check valve 44, so that when the solenoid 18 is excited with current, the core 39 can not be drawn upwardly by reason of the automatic closure of the ball-check valve and the consequent suction or pressure vacuum produced with- 25 in the cup 46 beneath the piston 42 in the chamber 45. The master electromagnet 61 comprises laminated frame 40' and the laminated core 60 to the upper end of which is secured a guiding rod or extension 62 of non-magnetic material. To the under side of the frame 40' 30 is rigidly secured the dash-pot cylinder 46' within which is adapted to move a piston 52 which is shown in this instance as having a pivoted connection 41' to the lower end of the core 60. The space above the piston 52 communicates with the atmosphere through the 35 passage 57 which is preferably near the upper side of the cylindrical portion of the dash-pot 46'. The space 45' beneath piston 52 communicates with the passage 58 at or near the lower end of the dash-pot 46', said passage being normally closed by the spring-pressed check 40 valve 59 which may be held in place by the support 60. If desired, the check valve 59 may be placed directly in the wall or bottom of the dash-pot 46', but in any event should be so arranged as to open outwardly so that when the coil 15 is excited and the core 60 drawn 45 upwardly, said valve will be held closed by its spring as well as by the effect of the suction or pressure vacuum produced by the piston 52 in the chamber 45'. It will be seen that the spaces beneath the pistons 42 are connected respectively by the pipes 49, 50 and 51 50 to the openings 54, 55 and 56 at different elevations in the wall of the dash-pot 46'. The drawing shows all of the electromagnets energized, which will occur when the lever 6 in the car is moved to one of its circuit-closing positions. In this case, the solenoids 15, 16, 17 and 55 18 are each endeavoring to lift their cores but can do so only to a certain extent, by reason of the dash-pot apparatus to which said cores are connected, the master electromagnet being stronger, however, will move its core up slightly to a comparatively greater distance 60 until connection is established between the passage 53 in the piston 52 and the opening 54, so that air may freely pass into the pipe 49 to the space beneath the piston 42 of the electromagnet switch 26. This switch will then be quickly closed to electrically connect the 65 fixed contacts 22', 23' and 24' to short-circuit the central

section of the opposition element R and thus allow the motor to increase in speed. When the core 60 is moved upwardly a little farther, communication is established between the passage 53 and the opening 55, so that air may enter the pipe 50 and allow the piston 42 to ascend 70 and thus effect the closure of the electric switch comprising the contact-maker 32 and the fixed contacts 29', 30' and 31'. The intermediate sections of the opposition element will thus be cut out and thus allow the motor to attain a higher speed. Finally the passage 53 75 registers with the opening 56 and the piston 42 is released so that the solenoid 18 may draw its core 39 upwardly and move the bridge-piece 36 into engagement with the contacts 33', 34' and 35' and thus entirely cut out all of the opposition element R, whereupon the 80 motor may attain full speed.

• Preferably the piston 52 should be so constructed that when the solenoid 15 is excited with current, it will be moved up at a rate of speed to effect a gradual acceleration of the motor M. If desired, a restricted 85 and adjustable aperture 64 may be placed in the lower portion of the dash-pot 46' in addition to the check valve, so that the rate of upward movement of the piston 52 may be regulated.

When the car switch is moved to central position, to 90 stop the motor, all of the electromagnets will be de-energized and by reason of the upwardly-opening check valve all of the pistons may freely descend, thus re-inserting the opposition element quickly and preventing a reversal of the motor while all of the opposition element is cut out. Furthermore, by reason of the rapid 95 re-insertion of the opposition element, a motor may again be started after being stopped, without any delay due to the motor-controlling apparatus.

The construction shown is merely illustrative of one 100 form of the embodiment of my invention, and it is obvious that various changes may be made by those skilled in the art and still fall within the spirit of my invention. I desire, therefore, not to be limited to the precise construction herein disclosed. 105

What I claim and desire to have protected by Letters Patent of the United States is:

1. The combination with a plurality of electro-magnets, of means for simultaneously energizing said electro-magnets, and means dependent upon fluid-suction for effecting 110 the successive operation of said electro-magnets.

2. The combination with a series of electro-magnets, of motor accelerating apparatus controlled thereby, and means electrically independent of said electro-magnets and dependent upon fluid-suction to effect the successive operation of said electro-magnets when the latter are energized. 115

3. The combination with a series of electro-magnets, of motor accelerating apparatus controlled thereby, and mechanically inter-connected mechanical means dependent upon fluid suction to control the successive operation of 120 said electro-magnets when the latter are energized.

4. In motor-controlling apparatus, the combination with an opposition element, of a normally open switch, an electro-responsive device for operating said switch, means dependent upon fluid-suctional apparatus for preventing 125 said device from closing said switch, and releasing mechanism for said means to effect the closing of said switch.

5. In motor-controlling apparatus, the combination with an opposition element connected to the motor, and means comprising fixed elements and movable elements and dependent upon formation of partial vacua for varying said opposition element to control the acceleration of said motor. 130

6. In motor-controlling apparatus, the combination of sectional starting resistance connected to the motor, elec- 135

- tro-responsive apparatus tending to cut out the entire starting resistance simultaneously, and fluid-suctional means for retarding and releasing said electro-responsive apparatus to effect a gradual acceleration of the motor.
5. In motor-controlling apparatus, sectional starting resistance connected to the motor, one or more switches for controlling said resistance, electric electromagnets for operating said switches tending to close the same when receiving current, and means dependent upon partial vacua to restrain the electro-magnets from closing the switches and to release them successively to effect a gradual acceleration of the motor.
8. In motor-controlling apparatus, the combination with a starting resistance, of one or more electromagnetic switches for controlling said resistance, suctional dash-pots each having one member fixed co-acting with said switches, and means for controlling said dash-pots to effect a successive actuation of said switches.
9. In alternating-current motor-controlling apparatus, the combination with an opposition element connected to the rotor of the motor, of one or more electromagnets connected to the mains leading to the stator of the motor, one or more switches operated by said electromagnets to control said opposition element, and fluid suctional apparatus for controlling said electromagnets and switches.
10. In alternating-current motor-controlling apparatus, the combination with a sectional opposition element in circuit with the rotor windings, of one or more single-phase electromagnets connected to the primary, switches operated by said electromagnets to cut out said opposition element step by step to effect the gradual acceleration of said motor, and fluid suctional apparatus for effecting a successive actuation of said switches.
11. In motor-controlling apparatus, the combination with a starting resistance, of a series of auxiliary electromagnets, switches operated by said electromagnets for controlling said resistance, a dash-pot connected to each electromagnet for preventing the same from closing the switch operated thereby, a main electromagnet, and means operated by said main electromagnet for controlling said dash-pots to effect a successive releasing of said series of electromagnets.
12. In motor-controlling apparatus, the combination with a main electromagnet, of a series of auxiliary electromagnets, a plurality of switches operated by said electromagnets, fluid suctional dash-pots for preventing said electromagnets from closing their switches, a sectional starting resistance connected to the motor, and means operated by said main electromagnet for controlling said dash-pots to effect a releasing of said electromagnets and the closing of said switches to cut out said resistance step by step to gradually accelerate said motor.
13. In motor-controlling apparatus, the combination with a starting resistance, of a switch for controlling said resistance, a main electromagnet, an auxiliary electromagnet for operating said switch, a fluid suctional dash-pot connected to said auxiliary electromagnet to prevent such switch from being closed when the auxiliary electromagnet is energized, an additional fluid suctional dash-pot connected to said main electromagnet, and means connect-
- ing said dash-pots for effecting a release of the auxiliary electromagnet to close its switch in a predetermined time after the main electromagnet has been energized.
14. In motor-controlling apparatus, the combination with a sectional starting resistance, of a plurality of switches for controlling said resistance, a plurality of electromagnets for operating said switches, a fluid suctional dash-pot connected to each of said electromagnets to prevent the same from closing its switch when said electromagnet is energized, an additional electromagnet, a fluid suctional apparatus operated by said additional electromagnet for successively releasing said first-named electromagnets to effect a step by step cutting out of the starting resistance and the gradual acceleration of the motor speed.
15. In motor-controlling apparatus, the combination with a starting resistance, of a plurality of switches for controlling said resistance, a plurality of electromagnets for operating said switches, a fluid suctional dash-pot connected to each of said electromagnets, an additional fluid suctional dash-pot connected to said additional electromagnet, and means establishing communication between said first-named dash-pot and said additional dash-pot.
16. In motor-controlling apparatus, the combination with a sectional starting resistance, of electric switches for controlling said resistance, a main electromagnet, auxiliary electromagnets for operating said switches, a plurality of cups or receptacles, means establishing communication between said first-named cups and said additional cup, and a piston in said additional cup having a passage therethrough to effect a successive actuation of said switches when the main electromagnet is energized.
17. In motor-controlling apparatus, the combination of a sectional starting opposition element connected to the rotor of the motor, of single-phase electromagnets connected to the primary of the motor, switches operated by said electromagnets, fluid suctional dash-pots to prevent the closing of said switches when said electromagnets are energized, an additional single-phase electromagnet, and fluid suctional apparatus operated by said additional electromagnet for effecting a successive releasing of the pistons of said first-named dash-pots and the successive closing of said switches to gradually accelerate said motor.
18. In an elevator, the combination with an induction motor, means for reversing said motor from the car, starting resistance connected to the rotor of said motor, a main electromagnet and a series of auxiliary electromagnets connected in a single-phase circuit leading to the mains supplying current to the motor, switches operated by said auxiliary electromagnets for controlling said resistance, and fluid suctional apparatus operated by said main and auxiliary electromagnets for effecting a successive closing of said switches to gradually accelerate the speed of said motor.
- In testimony whereof, I have signed my name to this specification in the presence of two subscribing witnesses. 115
